UNITED STATES PATENT OFFICE.

CLAUDE BOUCHER, OF COGNAC, FRANCE.

MACHINE FOR MAKING BOTTLES, &c.

SPECIFICATION forming part of Letters Patent No. 711,818, dated October 21, 1902.

Application filed December 31, 1901. Serial No. 87,910. (No model.)

To all whom it may concern:

Be it known that I, CLAUDE BOUCHER, a citizen of the Republic of France, residing at Cognac, in the Republic of France, have invented certain new and useful Improvements in or Relating to Machines for Making Bottles and other Articles of Blown Glass, of which the following is a specification.

The present invention relates to a machine for making bottles and other articles of blown glass, and comprises two measuring-molds, two molds for forming the neck, and two mouth-forming plungers which are arranged to work alternatively, so that they cannot be overheated to such a degree that the glass might adhere to the walls of the molds.

My invention in its preferred embodiment is illustrated in the accompanying drawings, wherein—

Figure 1 is a horizontal section taken on line xx just above the base of the machine, Fig. 2 is a vertical view taken on line A B, Fig. 1. Fig. 3 is an enlarged section through the neck-molds, their supporting-arms, and associated parts. Fig. 4 is a vertical sectional view taken on line C D, Fig. 1, looking toward the left, Fig. 2. Fig. 5 is a similar view taken on line E F, Fig. 1, looking to the right, Fig. 2, both of the measuring and one of the neck molds being shown open.

Referring to the drawings, 1 is the base-plate of the machine, having two standards 2 and 58 thereon. At the top of standard 2 and arranged in bearings 31 31, provided with oil-cups 35 35, is a rotatable horizontal hollow shaft 3, having a fixed extension 50, said shaft 3 being provided with hand-wheel 30, keyed at one end, and a face-plate 4, carrying measuring-molds $a a'$ at each extremity, at the other end, said face-plate being provided at its center with a boss 5, having two bent arms 6 6, carrying the neck-molds 20 and 20'. The measuring-molds $a a'$, each formed in two parts, are fixed to the face-plate 4 by means of adjustable screw-bolts 11 passing through slots 16 (see Fig. 5) in said face-plate and are held in position by lock-nut 17. The slots 16 allow of vertical adjustment of the measuring-molds. The two parts of the said molds are brought together for closing the molds and are moved apart when opening the molds by means of a toothed wheel 8, engaging two

pinions 9 9, mounted on a shaft 10, which passes through the arms of the mold parts and the inner ends of bolts 11 11. The pinions 9 are fixed to the arms of the mold parts and are operatively connected to the intermediate wheel 8, which is loosely mounted on a short axle d . This arrangement enables the operator to close the mold by moving one mold part by means of a handle 12 attached thereto, movement being transmitted to the other part through the gearing. The two halves constituting the mold are held in closed position by means of a hook or catch 13 in one part engaging a hole 14 in the other. A bottom part 15 (see Fig. 5) is adapted to close the open end of the measuring-molds when they are in their closed position by turning handles 44 thereon and inserting them in the slot 45 (see Fig. 5) of the mold halves.

In Fig. 2 the measuring-mold a' is shown in its open position with its inlet-opening turned downward, while the measuring-mold a appears in the position it occupies after a quantity of glass sufficient for the manufacture of the article to be obtained has been poured into it. It is while the mold is in this position that the molten glass therein is compressed by means of a steam or compressed air-jet in order to obtain a homogeneous mass and to enable delicate ornaments and inscriptions to be produced by causing the glass to adapt itself more perfectly to the shape of the mold. The steam or compressed air by opening valve s through the operation of treadle q passes from pipe t , communicating with any suitable source, to pipe o , thence through movable bracket g , carried by standard 58, and finally from funnel h to the measuring-mold. The measuring-molds are sufficiently large to enable the glass to be readily introduced into them and terminate at their opposite ends in a neck or collar, which when the mold is in its closed position fits against its corresponding neck-mold 20 20', one carried on each of the bent arms 6 6 of boss 5. In Fig. 2 measuring-mold a is shown in engagement with neck-mold 20. Each neck-mold, like its corresponding measuring-mold, is formed of two parts hinged together and consists of a casing 21, divided longitudinally into two parts, and of a mold proper arranged inside, which has the exact form to be given

the neck of the bottle. The two parts of each mold are adapted to be fastened together when the mold is in its closed position by engaging hook 25 on one part with hole 26 on 5 the other. In Fig. 5 the parts are shown in their open position. The neck-molds 20 20' and the measuring-molds *a a'* are moved alternately into the position for receiving the molten glass, in which position the opening 10 of the measuring-mold is at the top. This movement is effected by means of a hand-wheel 30, keyed to hollow shaft 3, actuating the face-plate 4, and boss 5, forming part thereof. To secure the measuring-molds in 15 their respective vertical positions, a recess 18 is provided at each extremity of the face-plate 4, and after the latter has been rotated through an angle of one hundred and eighty degrees said recess 18 bears against a roller 33 20 of a locking-bar 32, which is pressed upward by a spiral spring 34, as clearly shown in Fig. 5. When the measuring-mold is in its lower position, compressed air for blowing the bottle passes from the pipes *t* and *u* through stuff- 25 ing-box *v* into the hollow rotatable shaft 3 through a fixed extension 50, Fig. 3, of said shaft, and thence through the bent arm 6 in the direction of the arrows to the neck-mold in the lower position. Extension-shaft 50 is 30 fixed and is secured in standard 58 by nuts 23 23, and near its hollow end is formed in the shape of a crank-shaft 22, on which is a bushing 29. A collar 28, embracing said bushing, supports two mandrels 27 27, terminating in 35 screwed rods, which are recessed in the collar at diametrically opposite points. Said mandrels are moved alternately into the neck-molds 20 20' immediately before the introduction of the glass into the measuring-mold by 40 the longitudinal movement transmitted to sleeve 28 by the movement of hand-wheel 30. The mandrel 27 is inserted into the neck-mold 20 or 20' when the mold takes up its upper position below the measuring-mold, as may be 45 readily seen from Fig. 5, in which the neck-mold is shown open. When one of the mandrels is inserted into the neck-mold 20 in the upper position, the other is withdrawn from the neck-mold 20' in the lower position to allow 50 low compressed air to enter the cavity formed by the mandrel. The mandrels 27 have a diameter corresponding to the upper part of the neck of the bottle and are made to fit exactly with the inwardly-projecting flange 21' of the 55 neck-molds, though not quite filling the guide-sleeve 24. It is obvious that by this arrangement the compressed air is enabled to enter the neck-mold through guide-sleeve 24 and after the completion of the perforation of the 60 neck part of the bottle by the mandrel to enter the bottle itself when the mandrel has been removed from contact with flange 21', thus forcing the glass against the walls of the mold. At the same time the compressed air is prevented 65 from entering the upper neck-mold, as the corresponding mandrel is in contact with flange 21' of said neck-mold. Moreover, as the ex-

tension-shaft 50 is provided with only one opening on its lower side (see Fig. 3) the compressed air can pass only to the lower arm 6. 70

A finishing-mold *c* is supported by adjustable threaded bolts 39, which pass through standard 58, to which they are fixed by nuts 46. The axle 40, which passes through the heads of the bolt, receives the hinge-arms 36 75 of the finishing-mold parts. A slot *j*, provided in the standard 58, enables the finishing-mold to be adjusted vertically, according to its length and special form, so that the neck always joins exactly the neck-mold in its 80 lower position. For closing and opening the finishing-mold the two parts may be brought together or moved apart by means of a hand-wheel 57, operating a shaft 59, to the end of which a wheel 37 is keyed to transmit the 85 movement to pinions 38, arranged on the hinge-arms 36 of the finishing-mold. The shaft 59, carrying the wheel 57, turns freely in a sleeve *k*, formed with a stud passing through the central slot of the standard. This 90 sleeve *k* is held in position with regard to the standard by bolts 60, which are arranged to pass through a flange provided on the sleeve and through side slots.

The manufacture of bottles and other similar articles by means of the machine in question will now be described. One of the measuring-molds is placed by means of the hand-wheel in its upper position, as shown in Fig. 2, whereby the mandrel is automatically inserted through the crank-shaft into the neck-mold situated underneath this measuring-mold. After this has been done the operator introduces a quantity of glass necessary for producing the bottle or other article desired 105 into the mold, whereupon the operator moves the funnel *h* by means of the handle *i*, so as to close the opening of the measuring-mold. By actuating the treadle *q* and opening thereby the valve *s* compressed air is admitted 110 above the glass, which by this means becomes homogeneous and is applied in an efficient manner to the neck-mold situated underneath the measuring-mold, so as to enable the collar and other ornaments to be formed in a 115 perfect manner. This operation of compression ought to be made rapidly, so as to enable the glass to remain plastic. The operator now removes the funnel *h*, which then moves to the position shown in Fig. 4, and places the 120 bottom part 15 on the inlet-opening of the measuring-mold *a*. The mold is now brought into its lower position by turning the hand-wheel 30. During this half-revolution, by which the position of the measuring-mold is 125 changed, the crank-shaft 22 causes one of the mandrels to enter the neck-mold on reaching its upper position, while at the same time the mandrel of the neck-mold which is moved downwardly is withdrawn, so as to allow compressed air to pass through the sleeve 24. The mandrel having thus been withdrawn from the cavity made in the glass at the neck 130 of the orifice, the second treadle *p* is now op-

- erated to open the valve r , whereby compressed air is admitted from the supply-conduit t , communicating with a compressed-air reservoir or any other convenient source.
- 5 After the glass has been sufficiently solidified by the action of the compressed air and by contact with the walls and bottom of the mold the operator removes the bottom part 15 and opens the mold by disengaging the hook 13 on 10 one half from the hole 14 on the other. The rough bottle 60 is now suspended by its neck from the neck-mold 20. The operator then places the holder b against the bottom of the rough bottle 60 and by admitting a small 15 quantity of air into the interior of the bottle causes its lower end to assume the exact form of the holder, by which means the desired homogeneity of the material of the bottle is obtained. After the rough bottle 60 has assumed 20 its proper length, so as to bear upon the bottom part 47 of the finishing-mold, the operator closes the finishing-mold by turning the hand-wheel 57, whereby the two mold-valves fit closely around the bottom part 47, 25 which has been raised through the medium of lever 53, and inclose the rough bottle, which now receives its final form by the introduction of compressed air, which is admitted by actuating the treadle p and opening the valve r of 30 the compressed-air-supply tube u . After the bottle has received its final form in consequence of the glass having been forced against the walls and the bottom of the finishing-mold by the action of the compressed air the 35 mold is opened by disengaging the retaining means 42 43, so as to occupy the position represented in Fig. 4. Then the neck-mold is opened by removing the hook 25 from its hole 26, with which it was engaged. In the case 40 of bottles having a flat or concave bottom the manufacture is finished; but if the bottle is to be provided with a recess in the bottom a suitable auxiliary device for deepening the recess to the depth desired may be used.
- 45 I claim—
1. In a machine for manufacturing bottles or similar articles of blown glass, two measuring-molds, two neck-molds, two mouth-forming mandrels, and a single finishing-mold 50 with which said measuring-molds, neck-molds and mandrels are adapted to work alternatively.
  2. In a machine for manufacturing bottles, or similar articles of blown glass, a rotatable carrier, a central boss projecting therefrom, branch arms both extending from said boss on the same side of the carrier, two neck-molds one on each of said arms, two body-molds on the carrier at opposite sides of the 55 boss adapted to fit the neck-molds respectively.
  3. In a machine for manufacturing bottles or similar articles of blown glass, a rotatable carrier, a central boss projecting therefrom, two branch arms both extending from said boss on the same side of the carrier, two neck-molds one on each of said arms adapted to support the bottle after the measuring-molds have been disengaged therefrom, two measuring-molds on the carrier at opposite sides 60 of the boss adapted to join the neck-molds respectively, and a single finishing-mold adapted to close about the bottles in succession as they are brought to proper position by rotation of the carrier and the measuring-molds disengaged therefrom.
  4. In a machine for manufacturing bottles or similar articles of blown glass, a rotatable carrier, two neck-molds on the carrier adapted to support the bottle after the measuring-molds have been disengaged therefrom, two measuring-molds each composed of separable parts hinged to the carrier and adapted when closed to join the neck-molds respectively, and a single finishing-mold composed 85 of separable parts hinged to a fixed part of the machine and adapted to be closed about the bottles in succession as they are brought to proper position by rotation of the carrier and the measuring-molds disengaged therefrom.
  5. In a machine for manufacturing bottles or similar articles of blown glass, a rotatable carrier, a central boss projecting therefrom, two branch arms both extending from said boss on the same side of the carrier, two neck-molds each composed of separable parts hinged to said branch arms respectively, two measuring-molds composed of separable parts hinged to the carrier at opposite sides of the 90 boss, said measuring-molds being adapted to join the neck-molds respectively.
  6. In a bottle-making machine, a hollow stationary shaft, a revoluble tubular branch arm device mounted thereon, neck-molds at the 105 ends of the arms respectively, mandrels operable in the neck-molds respectively, and a mandrel-actuating means.
  7. In a bottle-making machine, a hollow stationary shaft, a revoluble tubular branch arm device mounted thereon, neck-molds at the 110 ends of the arms respectively, mandrels operable in the neck-molds respectively, and a crank for operating the mandrels forming part of the stationary shaft.
- In testimony whereof I have signed my name to this specification in the presence of two subscribing witnesses.
